Joseph W. Bartlett, of New York, N.Y.

Letters Patent No. 2215 dated Nov 7, 1865

Design for the standard and cradle of a sewing machine.

The schedule referred to in these Letters Patent and making part of the same.

To all whom it may concern:

Be it known that I, Joseph W. Bartlett, of the City, County, and State of New York, have invented or produced a new and original Design for the Iron Standards and Cradle for Sewing Machines; and I do hereby declare that the following is a full and exact description thereof, reference being had to the accompanying drawings.

Figure 1. is a side elevation.

2. is a front elevation.

3. is a plan of the Cradle.

4. is a section (full size) of the Standards showing their morticed or fluted form.

I claim the Design for the Standards and Cradle for Sewing Machines, herein shown.

Witnessed,

W. H. Angell
J. Plant
